UNITED STATES PATENT OFFICE.

WILLIAM H. JAMOUNEAU, OF NEWARK, NEW JERSEY.

DESIGN FOR A SPOON, &c.

SPECIFICATION forming part of Design No. 20,942, dated July 14, 1891.

Application filed May 9, 1891. Serial No. 392,247. Term of patent 7 years.

To all whom it may concern:

Be it known that I, WILLIAM H. JAMOUNEAU, a citizen of the United States, residing at Newark, in the county of Essex and State of New Jersey, have invented and produced a new and original Design for Handles for Spoons, Forks, and other Articles technically known to the trade as "Flat Ware;" and I do hereby declare the following to be a full, clear, and exact description of the invention, such as will enable others skilled in the art to which it appertains to make and use the same, reference being had to the accompanying drawing, and to letters of reference marked thereon, which form a part of this specification.

The figure of the drawing is a front plan of a spoon of my improved design, of which the following is a specification, the one figure being deemed sufficient to fully illustrate the same.

The leading feature of the design consists of a spoon-handle, the shank of which is in the form of an Egyptian column entwined

with asp-like figures, which is surmounted by a woman's head, which is intended to represent Cleopatra.

In said drawing, *a* indicates the bowl of the spoon, *b* the shank thereof, and *c* the broad extremity of the handle. The shank has a ³⁰ shape representing a fluted column *d*, entwined with asps *e*, the members in the column terminating in lotus-shaped blossoms and buds *f* conventionalized, which have the appearance of a capital to the column. Above ³⁵ the capital is the representation of a woman's head and bust *g*, the face being in profile.

What I claim as new is—

The design for a fork or spoon handle, substantially as shown and described. ⁴⁰

In testimony that I claim the foregoing I have hereunto set my hand this 7th day of May, 1891.

WILLIAM H. JAMOUNEAU.
